ABSTRACT OF THE DISCLOSURE

2,5 - diphenylfurans, 2,5 - diphenylpyrroles and 2,5-diphenylthiophenes having auxochromic substituents in the 3 position are useful brighteners in laundry detergent compositions which contain an organic detergent and an alkaline builder salt and are particularly effective in brightening nylon and acetate fabrics.

BACKGROUND

With the recent and current changes and improvement in fabrics employed for clothing and other household fabrics, more efficient and less expensive chemicals are being sought to optically brighten such fabrics. Optical brightening of fabrics from detergent solutions requires fabric substantivity, alkaline stability, water solubility and a high degree of fluorescence. 2,5-diphenylheterocycle compounds: 2,5 diphenylfuran, 2,5 diphenylthiophene and 2,5 diphenylpyrrole, have been taught as optical brighteners for polystyrene and polyolefin plastics in U.S. Pat. 3,222,290, Braus et al. These materials, however, do not have desired brightening characteristics for fabrics via application from laundry detergent solutions. They are particularly deficient in proper fluorescence characteristics.

SUMMARY OF INVENTION

It has been discovered that 2,5 diphenylheterocycle compounds having auxochromic substituents in the 3 position are excellent optical brighteners for use in laundry detergents and can be synthesized very efficiently. These compounds have the general formula

wherein: A is an auxochromic substituent selected from the group consisting of (1) morpholino, (2) vinyl, (3) phenyl, (4) NR_2 wherein R is H or an alkyl, or hydroxy-alkyl, having 1 to 3 carbon atoms, (5) OR' wherein R' is alkyl, hydroxyalkyl or NR_2 -substituted alkyl wherein NR_2 is as defined above and the alkyls contain 1 to 4 carbon atoms and (6) $(\text{OC}_2\text{H}_4)_n$ wherein n is 2 to 25; X is O, S, NH or NCH_3 ; ar is phenyl, naphthyl sulfonate or phenyl having a substituent at the meta, para or both meta and para positions selected from the group consisting of chlorine, methoxy, sulfonate and NR_2 as defined above.

These compounds are employed in laundry detergent compositions based on organic detergents and alkaline builder salts.

DETAILED DESCRIPTION

Some of the 2,5 diphenylheterocycle compounds of this invention are known. See S. M. King et al., Journal of the American Chemical Society, vol. 73, pp. 2253-6 (1951). All of the members of the class of compounds of this invention can be synthesized by following the general procedures outlined below:

2

In general, nucleophilic species may be added to 1,2-dibenzoylethylene or ring-substituted dibenzoylethylene to give 1-substituted-1,2-dibenzoylethane compounds or the corresponding ring-substituted dibenzoylthanes. These compounds may be cyclized to furan, pyrrole, or thiophene derivatives. As an example, addition of morpholine to 1,2-dibenzoylethylene yields 1-morpholino-1,2-dibenzoylethane (I) which upon treatment with sulfuric acid in acetic anhydride produces 2,5-diphenyl-3-morpholinothiophene. Treatment of I with ammonia yields the corresponding pyrrole derivative and subjecting I to P_2S_5 gives 2,5-diphenyl-3-morpholinothiophene. Other nitrogen compounds which can be substituted for morpholine are NH_3 or NHR_2 wherein R is H or an alkyl, or hydroxy-alkyl, having 1 to 3 carbon atoms. The nucleophilic agent may also be varied to include oxygen compounds. For example, ethanol may be added to dibenzoylethylene to produce 1 - ethoxy - 1,2-dibenzoylethane which can be cyclized to produce 3-ethoxy-2,5-diphenylfuran. Carbonyls may also be used in this sequence to produce polyethoxylated 3-derivatives. For specific descriptions of this type reaction see R. E. Lutz, P. S. Bailey, and N. H. Shearer, Jr., J. Am. Chem. Soc., 68, 2224 (1946).

Synthesis of 3-phenyl-2,5-diphenylheterocyclic derivatives may be accomplished through cyclization of 1-phenyl-1,2-dibenzoylethane.

Another general method for the production of 3-substituted - 2,5 - diphenylheterocyclic derivatives of interest comes through conversion of the well-known (see Heterocyclic Compounds, vol. 1, editor R. C. Elderfield, John Wiley and Sons, Inc., New York, N.Y., 1950) 3-halo-derivatives to organometallic compounds. For example, reaction of these compounds with magnesium produces Grignard reagents which undergo many well known reactions. (See Grignard Reactions of Nonmetallic Substances, by M. S. Kharasch and O. Reinmuth, Prentice-Hall, Inc., New York, N.Y., 1954.) As a specific example, 3-bromo-2,5-diphenylfuran may be converted to the corresponding Grignard reagent which may then be carbonated with CO_2 to produce 3-carboxy-2,5-diphenylfuran. Reaction of the organometallic Grignard reagent with aldehydes or ketones produces alcohols which may be dehydrated to give vinyl derivatives of 2,5-diphenylfuran.

Specific examples of the brightener compounds employed in the laundry detergent composition of this invention are the following:

- (1) 2,5-diphenyl-3-morpholofuran
- (2) 2,5-diphenyl-3-vinylfuran
- (3) 2,3,5-triphenylfuran
- (4) 2,5-diphenyl-3,N,N-diethylaminofuran
- (5) 2,5-diphenyl-3,N,N-diethanolaminofuran
- (6) 2,5-diphenyl-3-ethoxyfuran
- (7) 2,5-diphenyl-3-deca(oxyethylene)furan
- (8) 2,5-di-p-chlorophenyl-3-morpholofuran
- (9) 2,5-di-p-aminophenyl-3-morpholofuran
- (10) 2,5-di-m,p-dichlorophenyl-3-morpholofuran
- (11) 2,5-diphenyl-3-morpholinopyrrole
- (12) 2,5-diphenyl-3-vinylpyrrole
- (13) 2,3,5-triphenylpyrrole
- (14) 2,5-diphenyl-3-N,N-diethylaminopyrrole
- (15) 2,5-diphenyl-3-N,N-diethanolaminopyrrole
- (16) 2,5-diphenyl-3-ethoxypyrrrole
- (17) 2,5-diphenyl-3-dicarbethoxypyrrrole
- (18) 2,5-di-p-chlorophenyl-3-morpholinopyrrole
- (19) 2,5-di-p-aminophenyl-3-morpholinopyrrole
- (20) 2,5-di-m,p-dichlorophenyl-3-morpholinopyrrole
- (21) 2,5-diphenyl-3-morpholinothiophene
- (22) 2,5-diphenyl-3-vinylthiophene
- (23) 2,3,5-triphenylthiophene
- (24) 2,5-diphenyl-3-N,N-diethylaminothiophene

- (25) 2,5-diphenyl-3-N,N-diethanolaminothiophene
- (26) 2,5-diphenyl-3-ethoxythiophene
- (27) 2,5-diphenyl-3-deca(oxyethylene)thiophene
- (28) 2,5-di-p-chlorophenyl-3-morpholinothiophene
- (29) 2,5-di-p-aminophenyl-3-morpholinothiophene
- (30) 2,5-di-m,p-dichlorophenyl-3-morpholinothiophene
- (31) 2,5-dinaphthylsulfonate-3-morpholinothiophene

It has been found that fluorescence properties desired for effective optical brightening of fabrics cannot be predicted from absorption data. In order to achieve proper fluorescence in the brightening compounds of this invention, there must be 3-position substituent other than H and it must not be one which is joined to the heterocyclic ring through a saturated carbon atom. These brightener compounds have been found to be alkali-stable and to have a high degree of fluorescence and of substantivity to cloth, particularly to nylon and acetate fabrics. It has been difficult to obtain brighteners which are substantive to such fabrics. The water solubility of these brightener compounds is also satisfactory.

These brightener compounds are employed at a level ranging from about 0.01% to about 1% of the laundry detergent composition. In addition to these brightener compounds, the laundry detergent compositions of this invention comprise at least about 10% of a mixture of an organic detergent and an alkaline builder salt in a ratio in the range of about 5:1 to about 1:20, preferably about 2:1 to about 1:10. This mixture can be as much as the balance of the composition. The organic detergent compounds and alkaline builder salts are more fully described below.

ORGANIC DETERGENTS

The organic detergent compounds which can be utilized in the detergent compositions of this invention are the following:

(a) Water-soluble soaps.—Examples of suitable soaps for use in this invention are the sodium, potassium, ammonium and alkanol-ammonium (e.g., mono-, di-, and triethanolammonium) salts of higher fatty acids (C_{10} — C_{22}). Particularly useful are the sodium and potassium salts of the mixtures of fatty acids derived from coconut oil and tallow, i.e., sodium and potassium tallow and coconut soaps.

(b) Anionic synthetic non-soap detergents.—A preferred class can be broadly described as the water-soluble salts, particularly the alkali metal salts, of organic, sulfuric acid reaction products having in their molecular structure an alkyl radical containing from about 8 to about 22 carbon atoms and a radical selected from the group consisting of sulfonic acid and sulfuric acid ester radicals. (Included in the term alkyl is the alkyl portion of higher acyl radicals.) Important examples of these anionic synthetic detergents are the sodium or potassium alkyl sulfates, especially those obtained by sulfating the higher alcohols (C_8 — C_{18} carbon atoms) produced by reducing the glycerides of tallow or coconut oil; sodium or potassium alkyl benzene sulfonates, in which the alkyl group can be a straight or branched chain and contains from about 9 to about 15 carbon atoms, preferably about 12-14 carbons; sodium alkyl glyceryl ether sulfonates, especially those ethers of the higher alcohols derived from tallow and coconut oil; sodium coconut oil fatty acid monoglyceride sulfates and sulfonates; sodium or potassium salts of sulfuric acid esters of the reaction product of one mole of a higher fatty alcohol (e.g., tallow or coconut oil alcohols) and about 1 to 6 moles of ethylene oxide; sodium or potassium alkyl phenol ethylene oxide ether sulfates, with 1 to 10 units of ethylene oxide per molecule and wherein the alkyl radicals contain from 8 to 12 carbon atoms; the reaction product of fatty acids esterified with isethionic acid and neutralized with sodium hydroxide where, for example, the fatty acids are derived from coconut oil; sodium or potassium salts of fatty acid amide of a methyl tauride in which the fatty acids, for

example, are derived from coconut oil; sodium and potassium salts of SO_3 -sulfonated C_{10} — C_{24} α olefins.

(c) Nonionic synthetic detergents.—One class of nonionic detergents can be broadly defined as compounds produced by the condensation of alkylene oxide groups (hydrophilic in nature) with an organic hydrophobic compound, which may be aliphatic or alkyl aromatic in nature. The length of the hydrophilic or polyoxyalkylene radical which is condensed with any particular hydrophobic group can be readily adjusted to yield a water-soluble compound having the desired degree of balance between hydrophilic and hydrophobic elements. A second class of nonionic detergents comprises higher fatty amides. A third class of nonionic detergents has semi-polar characteristics. These three classes can be defined in further detail as follows:

(1) One class of nonionic synthetic detergents is marketed under the trade name of "Pluronic." These detergent compounds are formed by condensing ethylene oxide

20 with a hydrophobic base formed by the condensation of propylene oxide with propylene glycol. The hydrophobic portion of the molecule which, of course, exhibits water insolubility, has a molecular weight of from about 1500 to 1800. The addition of polyoxyethylene radicals to this hydrophobic portion tends to increase the water solubility of the molecule as a whole and the liquid character of the product is retained up to the point where the polyoxyethylene content is about 50% of the total weight of the condensation product.

(2) Alkylphenol-polyethylene oxide condensates are condensation products of alkyl phenols having an alkyl group containing from about 6 to 12 carbon atoms in either a straight chain or branched chain configuration with ethylene oxide, the said ethylene oxide being present 35 in amounts equal to 5 to 25 moles of ethylene oxide per mole of alkyl phenol. The alkyl substituent in such compounds may be derived from polymerized propylene, diisobutylene, octene, or nonene, for example.

(3) Nonionic synthetic detergents can be derived from the condensation of ethylene oxide with the product resulting from the reaction of propylene oxide and ethylene diamine and include compounds containing from about 40% to about 80% polyoxyethylene by weight and having a molecular weight of from about 5,000 to about 45 11,000. Such compounds result from the reaction of ethylene oxide with a hydrophobic base constituted of the reaction product of ethylene diamine and excess propylene oxide, said base having a molecular weight of the order of 2,500 to 3,000.

(4) Other nonionic detergents include condensation products of aliphatic alcohols having from 8 to 22 carbon atoms, in either straight chain or branched chain configuration, with ethylene oxide, e.g., a coconut alcohol-ethylene oxide condensate having from 5 to 30 moles of ethylene oxide per mole of coconut alcohol.

(5) The ammonia, monoethanol and diethanol amides of fatty acids having an acyl moiety of from about 8 to about 18 carbon atoms are useful nonionic detergents. These acyl moieties are normally derived from naturally occurring glycerides, e.g., coconut oil, palm oil, soybean oil and tallow, but can be derived synthetically, e.g., by the oxidation of petroleum or by hydrogenation of carbon monoxide by the Fischer-Tropsch process.

(6) Semi-polar nonionic detergents include long chain tertiary amine oxides corresponding to the following general formula

70 wherein R^1 is an alkyl radical of from about 8 to about 18 carbon atoms, R^2 and R^3 are each methyl, ethyl or hydroxyethyl radicals, R^4 is ethylene, and n ranges from 75 0 to about 10. The arrow in the formula is a conventional

representation of a semi-polar bond. Specific examples of amine oxide detergents include dimethyldodecylamine oxide and bis-(2-hydroxyethyl) dodecylamine oxide.

(7) Other semi-polar nonionic detergents include along chain tertiary phosphine oxides corresponding to the following general formula $RR'R''P\rightarrow O$ wherein R is an alkyl, alenyl or monohydroxyalkyl radical containing from 10 to 20 carbon atoms and R' and R'' are each alkyl or monohydroxyalkyl groups containing from 1 to 3 carbon atoms. The arrow in the formula is a conventional representation of a semi-polar bond. Examples of suitable phosphine oxides are found in U.S. Pat. 3,304,263 which issued Feb. 14, 1967, and include: dimethyldodecylphosphine oxide and dimethyl-(2-hydroxydodecyl) phosphine oxide.

(8) Still other semi-polar nonionic synthetic detergents include long chain sulfoxides having the formula

wherein R⁵ is an alkyl radical containing from about 10 to about 28 carbon atoms, from 0 to about 5 ether linkages and from 0 to about 2 hydroxyl substituents, at least one moiety of R⁵ being an alkyl radical containing 0 ether linkages and containing from about 10 to about 18 carbon atoms, and wherein R⁶ is an alkyl radical containing from 1 to 3 carbon atoms and from one to two hydroxyl groups. Specific examples of these sulfoxides are: dodecyl methyl sulfoxide and 3-hydroxy tridecyl methyl sulfoxide.

(d) Ampholytic synthetic detergents can be broadly described as derivatives of aliphatic secondary and tertiary amines, in which the aliphatic radical can be straight chain or branched alkyls and wherein one of the aliphatic substituents contains from about 8 to 18 carbon atoms and one contains an anionic water solubilizing group, e.g., carboxy, sulfo, sulfato, phosphato, or phosphono. Examples of compounds falling within this definition are sodium-3-dodecylaminopropionate and sodium-3-dodecylaminopropane sulfonate.

(e) Zwitterionic synthetic detergents can be broadly described as derivatives of aliphatic quaternary ammonium, phosphonium and sulfonium compounds, in which the aliphatic radical can be straight chain or branched alkyl, and wherein one of the aliphatic substituents contains from about 8 to 24 carbon atoms and one contains an anionic water solubilizing group, e.g., carboxy, sulfo, sulfato, phosphato or phosphono. Examples of compounds falling within this definition are 3-(N,N-dimethyl-N-hexadecylammonio) propane-1-sulfonate and 3-(N,N-dimethyl-N-hexadecylammonio)-2-hydroxy propane-1-sulfonate which are preferred for their cool water detergency characteristics. See, for example, Snoddy et al., Canadian Pat. 708,148.

These soap and non-soap anionic, nonionic, ampholytic and zwitterionic detergent compounds can be used singly or in combination. The above examples are merely illustrations of the numerous suitable detergents. Other organic detergent compounds can also be used.

BUILDER SALTS

The detergent compositions of this invention also contain water-soluble, builder salts either of the organic or inorganic types.

Examples of suitable water-soluble, inorganic alkaline detergency builder salts are alkali metal carbonates, borates, phosphates, polyphosphates, bicarbonates, silicates and sulfates. Specific examples of such salts are sodium and potassium tetraborates, perborates, bicarbonates, carbonates, tripolyphosphates, pyrophosphates, orthophosphates and hexametaphosphates.

Examples of suitable organic alkaline detergency builder salts are: (1) Water-soluble aminopolyacrylates, e.g., sodium and potassium ethylenediaminetetraacetates, nitrilotriacetates and N-(2-hydroxyethyl)-nitrilo diacetates; (2) water-soluble salts of phytic acid, e.g., sodium and potassium phytates—see U.S. Pat. 2,739,942; (3)

water-soluble polyphosphonates, including specifically, sodium, potassium and lithium salts of ethane-1-hydroxy-1,1-diphosphonic acid, sodium, potassium and lithium salts of methylene diphosphonic acid, sodium, potassium and lithium salts of ethane-1,1,2-triphosphonic acid. Other examples include these alkali metal salts of ethane-2-carboxyl-1, 1-diphosphonic acid, hydroxymethanediphosphonic acid, carbonyldiphosphonic acid,

- 10 ethane-1-hydroxy-1,1,2-triphosphonic acid, propane-1,1,3,3-tetraphosphonic acid, propane-1,1,2,3-tetraphosphonic acid, and propane-1,2,2,3-tetraphosphonic acid; (4) water-soluble salts of polycarboxylate polymers and copolymers as described in the patent of Francis L. Diehl, U.S. 3,308,-
15 067 issued Mar. 7, 1967. Specifically, a detergent builder material comprising a water-soluble salt of a polymeric aliphatic polycarboxylic acid having the following structural relationships as to the position of the carboxylate groups and possessing the following prescribed physical characteristics: (a) a minimum molecular weight of about 350 calculated as to the acid form; (b) an equivalent weight of about 50 to about 80 calculated as to acid form; (c) at least 45 mole percent of the monomeric species
20 having at least two carboxyl radicals separated from each other by not more than two carbon atoms; (d) the site of attachment to the polymer chain of any carboxy-containing radical being separated by not more than three carbon atoms along the polymer chain from the site of attachment of the next carboxyl-containing radical. Specific examples are polymers of itaconic acid, aconitic acid, maleic acid, mesaconic acid, fumaric acid, methylene malonic acid, and citraconic acid and copolymers with themselves and other compatible monomers such as ethylene.
25
30 Mixtures of organic and/or inorganic builders can be used and are generally desirable. One such mixture of builders is disclosed in Canadian Pat. 755,038 of Burton H. Gedge, e.g., ternary mixtures of sodium tripolyphosphate, trisodium nitrilotriacetate and trisodium ethane-1-hydroxy-1,1-diphosphonate. The above described builders
35 can also be utilized singly in this invention.

The preferred builders are sodium tripolyphosphate and sodium nitrilotriacetate, alone or in admixture. The preferred organic detergents are the anionic sulfate and sulfonates. The detergent compositions preferably provide
40 pH's in the range of about 8.5 to about 11.5.

The laundry detergent compositions of this invention can contain, if desired, in addition to the brightener, organic detergent and builder, any of the usual additives for such compositions which make them more attractive or effective. For example, perfumes, dyes, proteolytic enzymes, corrosion inhibitors, oxygen and chlorine bleaches, soil redeposition agents and other brighteners can be used. Diluents such as water, moisture and sodium sulfate can also be used to make up any balance of a composition comprising brightener, organic detergent and alkaline builder salt.

The 2,5-diphenylfurans and 2,5-diphenylthiophenes having a non-nitrogen-containing substituent in the 3-position or in the phenyl groups comprise a special sub-class of the brightener compounds of this invention which are significantly more stable to attack by hypochlorite comprising brightener, organic detergents and alkaline roles and those 2,5-diphenylthiophenes and 2,5-diphenylfurans having a nitrogen-containing group in the 3-position or in the phenyl group. Thus this stable sub-class of brighteners is advantageously employed in laundry detergent compositions which contain from about 0.5% to about 25%, usually 3-17%, of an active-chlorine containing bleaching compound. Examples of such compounds are: dichlorocyanuric acid; 1,3-dichloro-5,5-dimethyl hydantoin; N,N'-dichlorobenzoylene urea; para-toluene sulfondichloroamide; trichloromelamine; N-chloromelamine; N-chlorosuccinimide; N,N'-dichloroazodarbonamide; N-chloroacetyl urea; N,N'-dichlorobiuret; 55 chlorinated dicyandiamide; sodium hypochlorite; calcium

hypochlorite; lithium hypochlorite; chlorinated trisodium phosphate. Preferred compounds are dichlorocyanurates, i.e., dichlorocyanuric acid and the sodium and potassium builder salt.

Preparations of exemplary 3-substituted-2,5-diphenyl-heterocyclic optical brighteners of this invention are described as follows, with the Roman numerals designating the compounds of Table I below:

3-amino-2,5-diphenylpyrrole (I)

This compound has been prepared by two methods which are listed in order of preference:

(a) From 1,2-dibenzoylethylene.—1,2-dibenzoylethylene (6.0 g.; 0.025 m.) and 100 ml. of 15–40% alcoholic ammonia were placed in a vented glass liner. The liner was placed in a 500 ml. autoclave and heated for 16 hours. The temperature was varied from 60–160° C. with no effect on yield which was 25% of theoretical or 1.4 gm. Filtration of the reaction mixture gave 0.8 gm. and column chromatography over silica gel provided an additional 0.6 gm., M.P. 182–184° C. Elemental analysis: C=82.0 percent; H=5.8 percent; N=11.7 percent. Spectral data: $\lambda_{\text{max}}=340$; $\epsilon_{\text{max}}=23,000$; fluorescence max. =447. Absorption maxima (λ_{max}) and fluorescence maxima are given here and subsequently in nanometers.

(b) From 2,5-diphenylpyrrole.—2,5-diphenylpyrrole (2 gm.; ~0.01 mole) was dissolved in 100 ml. of acetic acid and concentrated nitric acid added dropwise. The resulting solution was stirred for 30 min. at room temperature and then poured into 20 ml. of water. This mixture was extracted with diethyl ether and the ether layer washed with 10% sodium carbonate solution. After drying with MgSO_4 , the ether layer was evaporated to give a residue which appeared to be 3-nitro-2,5-diphenylpyrrole from its infrared and ultraviolet absorption spectra. This product was dissolved in 20 ml. acetic acid-20 ml. ethanol to produce a solution to which 4.6 gm. of zinc powder was added. The resulting mixture was stirred for 18 hr. whereupon it was filtered and the filtrate poured into 100 ml. of water. Extraction of this mixture with chloroform followed by recovery of product gave a residue with the same spectral properties as 3-amino-2,5-diphenylpyrrole.

3-amino-2,5-diphenylfuran (II)

The compound was synthesized by an eight-step procedure using standard organic reaction as follows:

(1) To a suspension of 1,2-dibenzoylethylene (19.0 g.; 0.08 M) in 100 ml. of glacial acetic acid was added a solution of anhydrous HBr (10 g.; 0.12 M) dissolved in 40 ml. of glacial acetic acid. The resulting solution was stirred for 1/2 hr. at room temperature and then poured into 200 ml. of water to precipitate the product which was removed by filtration. The solids were washed three times with distilled water and then recrystallized from 400 ml. of ethanol-acetone mixture. There was obtained 19.8 g. of 1-bromo-1,2-dibenzoylethane (M.P.=138–139° C.).

(2) 1-bromo-1,2-dibenzoylethane (18 g.; 0.057 M) was suspended in 80 ml. of acetic anhydride and treated with 1.5 ml. of conc. H_2SO_4 . The temperature rose to 40° C. producing a red homogenous solution. The solution was stirred for 1/2 hour and then poured into 250 ml. of ice-water mixture. Filtration of the precipitate was followed by recrystallization from methanol. There was obtained 11 g. of 3-bromo-2,5-diphenylfuran (M.P.=83–84° C.).

(3) A solution of 3-bromo-2,5-diphenylfuran (20 g.; 0.067 M) in 65 ml. of tetrahydrofuran was added dropwise to magnesium metal (1.6 g.; 0.067 M) suspended in 10 ml. of tetrahydrofuran. After addition was complete the solution was refluxed for 1 hour.

(4) The resulting solution of Grignard reagent was carbonated by pouring onto ~150 grams of solid CO_2 (Dry Ice). After the Dry Ice evaporated, the mixture was

poured into water, acidified with dilute HCl and extracted with chloroform. Some solids did not dissolve in either solvent phase and were removed by filtration. These solids and the residue from the evaporation of the chloroform layer were combined and recrystallized from benzene. A yield of 12 g. of 2,5-diphenyl-3-furoic acid was realized. M.P.=221–222° C.

(5) 2,5-diphenyl-3-furoyl chloride: A solution of 2,5-diphenyl-3-furoic acid (5.0 g.; 0.02 M) dissolved in 50 ml. of thionyl chloride was refluxed for 1/2 hr. The excess thionyl chloride was distilled off under aspirator vacuum, the last remnants being removed as an azeotrope with benzene.

(6) 2,5-diphenyl-3-furoyl isocyanate: 2,5-diphenyl-3-furoyl chloride (5.5 g.; 0.2 M) was dissolved in 75 ml. acetone and cooled to 0° C. A solution of sodium azide (2.0 g.; 0.03 M) in 7 ml. of water was added dropwise while the reaction temperature was maintained at 0–10° C. The reaction mixture was stirred at room temperature for one hour and then poured into 100 ml. of water. The resulting solution was extracted with ethyl ether to isolate the azide from the aqueous phase.

(7) The ether solution of the azide was dropped down an air-cooled condenser into a 500 ml. round-bottom flask containing 200 ml. of boiling benzene. The ether was allowed to distill off and the resulting benzene solution was refluxed for one hour. The benzene was stripped off under aspirator vacuum to afford 2,5-diphenyl-3-furoyl isocyanate.

(8) 3-amino-2,5-diphenylfuran: 2,5-diphenyl-3-furoyl isocyanate (4.8 g.; 0.007 M) was dissolved in 75 ml. of benzene. Concentrated HCl (10 ml.) was added to the solution which was then refluxed for 1 1/2 hours. The mixture was poured into water and extracted with ethyl ether to remove the unreacted isocyanate. The aqueous phase was neutralized with sodium bicarbonate and then extracted with chloroform. The evaporation of the chloroform yielded a residue which was identified by infrared and ultraviolet spectra and elemental analyses as being 3-amino-2,5-diphenylfuran.

Spectral data: $\lambda_{\text{max}}=345$; $\epsilon_{\text{max}}=16,000$; fluorescence max.=447.

3-ethoxy-2,5-diphenylfuran (III)

Triethylamine (7.5 g.; 0.075 M) was added to 150 ml. of absolute ethanol in a 250 ml., 3-necked round-bottom flask equipped with a drying tube, magnetic stirrer, condenser and gas dispersion tube. Anhydrous hydrogen chloride was passed into the solution to attain a pH of ~2–3. Addition of 1,2-dibenzoylethylene (10 g.; 0.0425 M) was followed by 18 hrs. reflux. The solution was cooled to 0° C. and the product removed by filtration. The product was dissolved in chloroform and water washed. Evaporation of the chloroform gave 3.0 gm. (percent yield=27%).

Elemental analysis: C=82.1%; H=6.2%; O=12.4%. Spectral data: $\lambda_{\text{max}}=340$; $\epsilon_{\text{max}}=25,700$; fluorescence max.=25,400.

3-ethoxy-2,5-di-p-chlorophenylfuran (IV)

This compound was prepared in a manner analogous to that of 3-ethoxy-2,5-diphenylfuran using 1,2-di-p-chlorobenzoylethylene as starting material. The yield of material was 51%. Spectral data: $\lambda_{\text{max}}=351$; $\epsilon_{\text{max}}=32,000$; fluorescence max.=410.

3-morpholino-2,5-di-p-chlorophenylfuran (V)

1,2-di-p-chlorobenzoylethylene (10.0 g.; 0.033 M) was suspended in 100 ml. of diethyl ether in a 250 ml. round-bottom flask equipped with a reflux condenser and magnetic stirrer. Morpholine (6.0 g.; 0.066 M) was added and the reaction heated to reflux for 2 hr. The mixture was cooled to 20° C. and 1-morpholino-1,2-di-p-chlorobenzoylethane, 10.7 g. (83%), collected by filtration. This product was suspended in 30 ml. of acetic anhydride and treated with 2 ml. conc. H_2SO_4 . The temperature rose to

50-55° C. producing a homogeneous solution. This solution was stirred for 2 hr. and then poured into an ice-water mixture. Neutralization with sodium carbonate was followed by extraction with chloroform. The chloroform solution was dried with anhydrous magnesium sulfate and evaporated to give a residue which was recrystallized from ethanol-acetone mixture to give a 66% yield of product.

Analytical data: C=65.5%; H=4.7%; Cl=18.4%; N=3.8%. Spectral data: $\lambda_{\text{max}}=345$; $\epsilon_{\text{max}}=30,000$; fluorescence max.=443.

3-morpholino-2,5-diphenylfuran

The compound was synthesized by the same procedure used for the corresponding dichloro compound, except that an equivalent amount of 1,2-dibenzoylethylene was used instead of 1,2-di-p-dichlorobenzoylethylene.

Spectral data: $\lambda_{\text{max}}=340$; $\epsilon_{\text{max}}=24,000$; fluorescence max.=430.

Brightener tests

Table I contains data obtained by washing unsoiled, fluorescer-free cloths of the fabrics indicated in 200 ml. of washing solution in a pint jar in a laundrometer for 30 min. at 130° F. The washing solutions were composed of 0.15% of the detergent composition as outlined below, water of 7 grain per gallon hardness, and the specified brightener compound (I-V) in the concentrations indicated. Tests were run at 3 parts per million of the brightener; however, Table I below also contains data at 6 and 9 p.p.m. The numbers are recorded under each fabric type in GM (Galvanek-Morrison Fluorimeter) units, with the larger numbers indicating better brightening results.

DETERGENT COMPOSITION

	Percent
Sodium linear dodecyl benzene sulfonate	7.8
Sodium tallow alkyl sulfate	9.5
Sodium tripolyphosphate	49.4
Sodium silicate	5.9
Na_2SO_4	13.7
Sodium carboxymethylcellulose	0.2
Nonionic suds controlling agents	2.2
Moisture	Bal.

3 p.p.m. brighteners in an aqueous solution of 0.15% of this composition is another way of reciting the use of 0.2% of the brightener in the full formulation listed above.

TABLE I

Brightener compound:	concentration, p.p.m.	GM units		
		Cotton	Nylon	Acetate
I	3	13	89	89
	6	15	84	128
	9	17	108	149
II	3	6	61	62
III	3	7	43	37
IV	3	-----	51	44
V	3	9	51	47
	6	9	79	84
	9	12	110	115

These data in GM units compare favorably with other available brightening compounds of different chemical types, which generally are difficult and expensive to synthesize.

The detergent (laundering and brightening) compositions of this invention are exemplified by the following examples which show different built formulations in which the 3-substituted 2,5-diphenylheterocycle brighteners can be employed. These compositions provide pH's in the range of 8.5-11.5. The invention is not limited by these examples, however, which are merely illustrative.

EXAMPLE 1

	Percent
Sodium soap of 20:80 coconut:tallow fatty acids	35
Sodium silicate	10
Tetrasodium pyrophosphate	40
Sodium chloride	6
3-amino-2,5-diphenylpyrrole	0.05
Moisture	Balance

This composition launders well and exhibits good brightening properties on nylon fabrics.

EXAMPLE 2

A granular built synthetic detergent composition having the following formulation can be prepared with the brightening agents of this invention incorporated therein. The composition, in addition to performing well in its cleaning capacity, imparts effective fluorescence to fabrics cleansed in the solution:

	Percent
20 Sodium linear dodecyl benzene sulfonate	17.5
Sodium tripolyphosphate	50
Sodium sulfate	14
Sodium carboxymethylcellulose	0.5
Sodium silicate	7
25 3-amino-2,5-diphenylfuran	0.10
Moisture	Balance

EXAMPLE 3

An excellent granular laundering and brightening composition has the following formula:

	Percent
Dimethyldodecylphosphine oxide	5
Condensation product of 11 moles of ethylene oxide with 1 mole of coconut fatty alcohol	10
Tetrasodium methylene diphosphonate	10
Sodium tripolyphosphate	60
Sodium carboxymethyl cellulose	0.5
Sodium silicate	10
3-ethoxy-2,5-diphenylfuran	0.20
Moisture	Balance

A water solution containing 0.15%, 0.3% and 0.45% concentrations of the above formula provides a very good cleaning and brightening results in household laundering of cotton, nylon and acetate fabrics.

EXAMPLE 4

The following granular composition containing an effective chlorine bleaching agent performs very well in cleaning, whitening and brightening:

	Percent
Sodium tallow alkyl sulfate	7
Sodium linear dodecylbenzenesulfonate	7
Sodium tripolyphosphate	50
55 Sodium carbonate	10
Sodium sulfate	10
Potassium dichlorocyanurate	15
3-ethoxy-2,5-di-p-chlorophenylfuran	0.05
3-vinyl-2,5-diphenylthiophene	0.05
60 Moisture	Balance

EXAMPLE 5

A built liquid laundering composition which brightens as it cleans and which is suitable for laundering household fabrics can have the following composition:

	Percent
Sodium-3-dodecylaminopropionate	6
Sodium linear dodecylbenzenesulfonate	6
70 Potassium pyrophosphate	20
Potassium toluene sulfonate	8
Sodium silicate	3.8
Carboxymethyl hydroxyethyl cellulose	0.3
3-morpholino-2,5-di-p-chlorophenylfuran	0.05
75 Water	Balance

11
EXAMPLE 6

Another built liquid detergent composition according to this invention has the following composition:

	Percent
Sodium linear dodecylbenzenesulfonate	6
Dimethyldodecylamine oxide	6
Trisodium ethane-1-hydroxy-1,1-diphosphonate	10
Tripotassium nitrilotriacetate	10
Potassium toluene sulfonate	8
Sodium silicate (ratio SiO ₂ :Na ₂ O of 2:1)	3.8
Sodium carboxymethyl cellulose	0.3
3-morpholino-2,5-diphenylfuran	0.20
Water	Balance

This detergent composition is effective in laundering and brightening resin-treated cotton "wash and wear" fabrics.

EXAMPLE 7

A household laundering composition can contain the following ingredients:

	Percent
Sodium salt of SO ₃ -sulfonated tetradecene	10
Dimethyl coconut alkyl ammonio acetate	10
Trisodium ethane-hydroxy triphosphonate	60
Sodium carbonate	10
3-morpholino-2,5-diphenylthiophene	0.10
Moisture	Balance

This composition brightens as it cleans and can be usefully employed in laundering nylon fabrics.

EXAMPLE 8

An effective granular detergent composition has the following formulation:

	Percent
Sodium linear dodecylbenzenesulfonate	7.5
Sodium tallow alkyl sulfate	2
Hydrogenated marine oil fatty acid suds depressant	2.2
Sodium tripolyphosphate	40
Trisodium nitrilotriacetate	20
Sodium silicate (ratio SiO ₂ :Na ₂ O of 2:1)	10
Sodium sulfate	13
3-vinyl-2,5-diphenylpyrrole	0.50
Water	Balance

EXAMPLE 9

Another effective granular detergent has the following composition:

	Percent
Sodium linear dodecylbenzenesulfonate	10
Condensation product of 1 mole of nonyl phenyl with 12 moles of ethylene oxide	50
Sodium tripolyphosphate	10
Trisodium ethane-1-hydroxy-1,1-diphosphonate	30
Trisodium nitrilotriacetate	10
Sodium silicate (ratio of SiO ₂ :Na ₂ O of 2:1)	6
Trisodium phosphate	10
Sodium carboxymethyl cellulose	0.5
3-phenyl-2,5-diphenylthiophene	0.1
3-diethanolamino-2,5-di-p-methoxyphenylfuran	0.2
Moisture	Balance

EXAMPLE 10

A laundering-brightening composition, especially effective on nylon and acetate fabrics at cool water temperatures, has the following composition:

	Percent
Sodium tallow alkyl sulfate	5
3-(N,N-dimethyl-N-dodecylammonio) - 2 - hydroxypropane-1-sulfonate	12
Sodium salt of SO ₃ -sulfonated- α -tridecene	5
Sodium tripolyphosphate	30
Trisodium nitrilotriacetate	20
Sodium silicate (SiO ₂ :Na ₂ O=1.61:1)	10
Sodium sulfate	75

12

Sodium carboxymethyl hydroxyethyl cellulose 0.3
3-deca(oxyethylene)-2,5-diphenylfuran 0.1
3-phenyl-2,5-diphenylpyrrole 0.1

EXAMPLE 11

Another effective cool water built granular composition according to this invention, particularly useful with resin-treated cotton fabrics, has the following composition:

	Percent
Sodium tallow alkyl sulfate	5
3-(N,N-dimethyl-N-hexadecylammonio)-propane - 1-sulfonate	5
Dimethyldodecylphosphine oxide	10
Trisodium ethane-1-hydroxy-1,1-diphosphonate	5
Trisodium nitrilotriacetate	10
Sodium tripolyphosphate	40
Sodium silicate (Na ₂ O:SiO ₂ =1:2.5)	10
Sodium carboxymethyl cellulose	0.3
Sodium sulfate	10
3-isopropoxy-2,5-di-m-aminophenylfuran	0.3
Moisture	Balance

The foregoing description of the invention has been presented describing certain operable and preferred embodiments. It is not intended that the invention should be limited since variations and modifications thereof will be obvious to those skilled in the art, all of which are within the spirit and scope of this invention.

30 What is claimed is:

1. A detergent composition consisting essentially of a mixture of a water-soluble organic detergent and an alkaline builder salt suitable for use with said detergent in a ratio range of about 5:1 to about 1:20 and an optical brightener having the formula:

45 wherein: A is an auxochromic substituent selected from the group consisting of (1) morpholino, (2) vinyl, (3) phenyl, (4) NR₂ wherein R is H or an alkyl, or hydroxyalkyl, having 1 to 3 carbon atoms, (5) OR' wherein R' is an alkyl group containing 1 to 4 carbon atoms and (6) (OC₂H₄)_n wherein n is 2 to 10; X is O, S, NH or NCH₃; ar is phenyl, or phenyl having a substituent at the meta, para or both meta and para positions selected from the group consisting of chlorine, methoxy and NR₂ as defined above.

2. The composition of claim 1 wherein X is O.

3. The composition of claim 2 wherein the organic detergent is a water soluble anionic sulfate or sulfonate detergent and wherein the alkaline builder is sodium tripolyphosphate, sodium nitrilotriacetate or mixtures thereof.

4. The composition of claim 3 wherein the brightener is 3-morpholino-2,5-di-p-chlorophenylfuran.

5. The composition of claim 3 wherein the brightener is 3-amino-2,5-diphenylfuran.

6. The composition of claim 1 wherein X is N.

7. The composition of claim 6 wherein the organic detergent is a water soluble anionic sulfate or sulfonate detergent and wherein the alkaline builder is sodium tripolyphosphate, sodium nitrilotriacetate or mixtures thereof.

8. The composition of claim 7 wherein the brightener is 3-amino-2,5-diphenylpyrrole.

9. The composition of claim 1 wherein the A, X and ar substituents are nitrogen-free and the composition con-

tains from about 0.5% to about 25% of an active chlorine-containing bleaching compound selected from the group consisting of potassium dichlorocyanurate and sodium dichlorocyanurate.

10. The composition of claim 9 wherein X is O, the organic detergent is a water-soluble anionic sulfate or sulfonate detergent, wherein the alkaline builder is sodium tripolyphosphate, sodium nitrilotriacetate or mixtures thereof and the bleaching compound is a dichlorocyanurate.
